UNITED STATES PATENT OFFICE.

EUGENE ATWOOD, OF STONINGTON, CONNECTICUT, ASSIGNOR TO THE ATWOOD-MORRISON COMPANY, OF STONINGTON, CONNECTICUT, A CORPORATION OF NEW JERSEY.

BOBBIN.

No. 851,211.

Specification of Letters Patent. Patented April 23, 1907.

Application filed September 27, 1906. Serial No. 336,402.

To all whom it may concern:

Be it known that I, EUGENE ATWOOD, a citizen of the United States, and a resident of Stonington, in the county of New London and State of Connecticut, have invented a new and useful Improvement in Bobbins, of which the following is a specification.

The object of this present invention is to provide a bobbin of novel construction whereby it is adapted to be used in connection with a winding machine without the use of a spindle and may then be removed from the winding machine and placed in a spinning machine by being directly engaged with the blade of the spinning spindle, the said bobbin being provided with a hollow tube the ends of which project beyond the bobbin heads for forming gudgeons when the bobbin is used in connection with a winding machine, the said tube also serving to snugly fit the blade of the spinning spindle when the bobbin is used in connection with a spinning machine.

My invention further contemplates a bobbin of the above character in which a flared recess is formed in one of the heads of the bobbin for receiving and frictionally engaging the tapered top of the whirl.

In the accompanying drawings, Figure 1 shows the bobbin in its horizontal position when used as a winding bobbin and Fig. 2 shows the bobbin in its vertical position in connection with a spinning spindle, certain of the parts being shown in section to more clearly illustrate the frictional engagement of the bobbin with the whirl.

The bobbin is denoted by 1 and it is provided with driving heads 2 and 3 formed integral therewith. These heads are fitted to be engaged by the usual driving drums 4 and 5 of a winding machine, which driving drums are indicated in dotted lines in Fig. 1.

A hollow tube 6 extends through the bobbin 1 and forms an integral part of the same. The ends of this tube project a short distance beyond the driving heads 2 and 3 of the bobbin so that the said projecting ends may form gudgeons for supporting the bobbin

when it is used in connection with a winding machine. This hollow tube 6 is arranged to snugly fit the blade 7 of a spinning spindle when the bobbin is used in connection with a spinning machine. The whirl of the spindle is denoted by 8 and it is provided with a tapered top 9 arranged to enter a flaring recess 10 in one of the driving heads of the bobbin, in the present instance the driving head 2.

It will be seen that a bobbin constructed as hereinabove described will permit of its being used both in connection with a winding machine and a spinning machine without the necessity of the insertion and removal of a winding spindle with heads adapted to drive the bobbin. The center tube not only forms the gudgeons for the bobbin when used in connection with a winding machine but also snugly fits the spinning spindle when used in connection with a spinning machine. Furthermore, additional friction required for causing the spindle to drive the bobbin properly is obtained by the frictional engagement of one of the bobbin heads with the whirl by providing the bobbin and head with the flared recess and the whirl with the tapered top.

What I claim is:

A bobbin used for winding and spinning, having driving heads formed integral therewith for engagement with the driving drums of a winding machine and a spinning spindle receiving tube projecting beyond the driving heads to form gudgeons for the bobbin when it is used for winding; one of the heads being provided with a flaring recess for receiving and frictionally engaging the tapered whirl of the spinning spindle.

In testimony, that I claim the foregoing as my invention, I have signed my name in presence of two witnesses, this 24th day of September 1906.

EUGENE ATWOOD.
